(21) Appl. No.: **29/346,741**

(57) **CLAIM**

(22) Filed: **Nov. 5, 2009**

The ornamental design for a tilt rod for a control system for window covering, as shown and described.

(51) **LOC (9) Cl.** 06-10

DESCRIPTION

(52) **U.S. Cl.** **D6/580**

FIG. 1 is an enlarged fragmentary perspective view of a tilt rod for a control system for window covering;

(58) **Field of Classification Search** ..... D6/577, D6/580, 582; D8/376, 382; 160/84.07, 126, 160/168.1 R, 168.1 V, 177, 307, 321, 323.1; D25/120, 122; 470/19; 156/256; 182/194; 165/183; 92/169.1; 52/836

FIG. 2 is an enlarged fragmentary front view thereof;

See application file for complete search history.

FIG. 3 is a rear view thereof;
